UNITED STATES PATENT OFFICE.

CARL M. JOSTED, OF MILWAUKEE, WISCONSIN.

RADIATOR CIRCULATING SYSTEM.

Application filed February 4, 1922. Serial No. 534,098.

To all whom it may concern:

Be it known that I, CARL M. JOSTED, a citizen of the United States, and resident of Milwaukee, in the county of Milwaukee, and State of Wisconsin, have invented certain new and useful Improvements in Radiator Circulating Systems; and I do hereby declare that the following is a full, clear, and exact description thereof.

10 The invention relates to cooling systems for engines. Hitherto difficulty has been experienced in automobiles by reason of a failure to get a proper cooling action on the cylinders with the circulating water; and 15 trouble has been occasioned at times because of the evaporation of the water and the consequent drying of the jacket, permitting the cylinder walls to become very hot.

The invention aiming to obviate these difficulties, consists of a reservoir having a considerable water capacity, yet so shaped as to be readily positioned between the radiator and the engine, and adjacent the fan.

20 Objects of the invention are to produce a greater cooling action on the cylinder walls; and to utilize the heat conducting tendencies of the walls of the reservoir to more effectively cool off the circulating water, and to effect a balancing action, the 25 water in the reservoir feeding out at a cooler temperature, while warmer water from the water jacket feeds therein.

Additional objects are the provision of a reservoir of such shape and dimensions as to have a considerable water capacity, yet adapted to be positioned between an engine and the radiator and adjacent the fan, a feature being the retention of standard parts in an unaltered condition.

30 Other objects are the provision of a reservoir simple in construction, easy to manufacture and durable.

Reference is had to the accompanying drawing, in which—

45 Figure 1 shows the reservoir in transverse cross section as applied to an engine.

Figure 2 is a plan view of the reservoir, and

50 Figure 3 is a side elevation thereof.

Water jacket 10, support 11, fan 12, radiator 13 and tubular support 14 leading therefrom, are of standard design. Reser-

voir 15 has a flat bottom 16 in which a plug 17 is threaded and vertical sides. The top is bent downwardly at 18 and from one side a nipple 19 is directed provided with ears 20, having openings 21 therein, thru which bolt 22 is directed for securing reservoir 15 to support 11. From the deformed portion 18 of the top, a nipple 23 extends upwardly at an incline, being received in hose 24 which is secured to tubular support 14, the inclination of the standard support 14 being the same as that of nipple 23. On the top of reservoir 15 is a vent 25, which 55 may be used in connection with plug 17 for draining the reservoir.

It will be noted that the dimensions and shape of the devices are such as to give it a considerable capacity, yet it is readily received in a small space provided in a standard structure.

While a preferred embodiment of the invention has been illustrated and described, it is to be understood that the present invention is not confined to such specific embodiment, but may be otherwise embodied within the spirit of the invention and the scope of the following claims, and it will further be understood that a substantial 75 range of equivalence is contemplated.

I claim:

1. In an automobile, the combination of an internal combustion engine having a water jacket provided with a forward flange, a fan located in front of and spaced from said engine, a radiator located in front of said fan and having a rearwardly and downwardly extending inlet, and an auxiliary reservoir comprising a rectangular tank located between said engine and fan and having an inlet provided with a rear flange bolted to said first mentioned flange and supported thereby and having an upwardly and forwardly extending outlet 85 aligning with the inlet of said radiator and connected therewith.

2. In an automobile, the combination of an internal combustion engine having a water jacket provided with a forward flange, a fan located in front of and spaced from said engine, a radiator located in front of said fan and having a rearwardly and downwardly extending inlet, an auxiliary reser-

voir comprising a rectangular tank located between said engine and fan and having an inlet provided with a rear flange bolted to said first mentioned flange and supported thereby and having an upwardly and forwardly extending outlet, aligning with the inlet of said radiator and connected therewith, said tank having a depressed bottom

located below said inlet to form a sediment chamber, and a drain plug in said bottom. 10

In testimony that I claim the foregoing I have hereunto set my hand at Milwaukee, in the county of Milwaukee and State of Wisconsin.

CARL M. JOSTED.
